UNITED STATES PATENT OFFICE.

DALLETH Z. MERCHANT, OF NORFOLK, VIRGINIA.

DESIGN FOR A TEXTILE FABRIC.

No. 38,153.

Specification for Design.

Patented July 31, 1906.

Application filed May 21, 1906. Serial No. 318,103. Term of patent 3½ years.

To all whom it may concern:

Be it known that I, DALLETH Z. MERCHANT, a citizen of the United States, residing at Norfolk, in the county of Norfolk and State of Virginia, have invented a new, original, and ornamental Design for Textile Fabrics, reference being had to the accompanying drawing, which shows a plan view of the fabric.

I claim—

The ornamental design for a textile fabric as shown.

DALLETH Z. MERCHANT.
